UNITED STATES PATENT OFFICE.

THOMAS E. WATERS AND RAY E. WATERS, OF HASTINGS, MICHIGAN.

DISPLAY DEVICE FOR CAPS.

Application filed March 27, 1922. Serial No. 546,998.

To all whom it may concern:

Be it known that we, THOMAS E. WATERS and RAY E. WATERS, citizens of the United States, residing at Hastings, Barry County, State of Michigan, have invented certain new and useful Improvements in Display Devices for Caps, of which the following is a specification.

This invention relates to improvements in display devices and storing devices for caps.

It is of special advantage for merchandizing purposes.

The object of the invention is to provide an effective support for a cap which will avoid the need of any special stuffing for the same and will support it effectively and in unruled condition.

Objects which pertain to details and economies of construction and operation will definitely appear from the detailed description to follow.

We accomplish the objects of our invention by the devices and means described in the following specification. The invention is clearly defined and pointed out in the claim.

A structure which is a preferred embodiment of our invention is fully illustrated in the accompanying drawing, forming a part of this application, in which:

Fig. I is a perspective view of a small cabinet to which our invention has been adapted, the door and cap holders being shown in open position by dotted lines.

Fig. II is a detail horizontal sectional view on line 2—2 of Fig. I, showing the position and arrangement of our improved cap supporter inside the cabinet.

Fig. III is a detail perspective view of the cap supporter detached from the cabinet.

Fig. IV is an enlarged detail sectional view on line 4—4 of Fig. II, showing the socket supporting member and its means of attachment to the door.

In the drawing similar reference numerals refer to similar parts throughout the several views, and the sectional views are taken looking in the direction of the little arrows at the ends of the section lines.

We will consider the numbered parts of

the drawing by the numbers. 1 is the cabinet provided with a door or doors 2, hinged by vertical hinges 3 at one side. 4 is one of the series of cap supports consisting of a looped wire inwardly projecting with an upwardly and rearwardly inclined portion 6 terminating in a broad rounded portion 5, which supports the back and upper crown of a soft cap in unruled condition in position with the forepiece and front of the cap ready for full display on opening the cabinet door. The front ends are formed in downwardly depending shanks 7, 7, which are retained in suitable sockets formed by the plate 8 which is retained in position by the screws 9.

In use it will be observed that the cap is placed firmly on its support with the forepiece to the rear when the cabinet is open, and with the rounded portion 5 extending into the upper back part of the cap distending and supporting the same effectively for inspection and display. The front and forepiece of the cap thus rest upon the horizontal portions of the support 4, and the cap is effectively supported in a natural position for display so that the cap can be inspected without being removed from its support. If removed from its support the cap can be very readily replaced. There is no need for any stuffing within the cap because the wire is so conformed that it supports the cap effectively without such means.

We have shown three of the supports, one above the other on the small door of the cabinet here illustrated. In use these doors are of considerable size, forming several rows with series of cap supports thereon, displaying each cap separately and in convenient position for removal and replacing. The back part of the cabinet is retained for caps which are stored in the flat and they can be readily placed upon the display support which holds them in perfect condition for display and inspection. Simply closing the door puts them all securely packed away free from dust and likelihood of injury.

While the support lends itself to use with a cabinet door it is usable on any wall or standard.

Having thus described our invention, what we claim as new and desire to secure by Letters Patent, is:

A cap support comprising a horizontal portion for supporting the front and fore-piece of a cap, an upwardly-projecting horizontally-curved portion conformed to the inner periphery of the cap top and adapted to project within the said cap top for support-

ing and distending the back and inner part 10 of the crown of the cap, and inclined portions extending to said horizontal portion for the bottom of the cap, as specified.

In witness whereof, we have hereunto set our hands and seals.

THOMAS E. WATERS. [L. S.]
